TRACHEOTOMY MASK

William R. King, Denver, Colo., assignor to Sandoz-Wander, Inc., Hanover, N.J.

Continuation-in-part of abandoned design application Ser. No. 149,403, May 28, 1971. This application Nov. 10, 1971, Ser. No. 197,645

Term of patent 14 years

Int. Cl. D24—01

U.S. Cl. D83—1 K

FIG. 1

FIG. 2

FIG. 3

FIG. 4

FIG. 1 is a side elevation view of the tracheotomy mask;

FIG. 2 is a front end elevational view of the tracheotomy mask, looking to the left in FIG. 1;

FIG. 3 is a rear end elevation view of the tracheotomy mask, looking to the right of FIG. 1;

FIG. 4 is an isometric view of the tracheotomy mask.
This is a continuation-in-part of design application Ser. No. D. 149,403, filed May 28, 1971 and now abandoned.

I claim:

The ornamental design for a tracheotomy mask, as shown.
